[57] CLAIM

The ornamental design for a printer platen, as shown and described.

DESCRIPTION

FIG. 1 is a perspective view of a printer platen showing our new design;

FIG. 2 is an enlarged right side elevational view thereof;

FIG. 3 is an enlarged left side elevational view thereof; FIG. 4 is a rear elevational view thereof;

FIG. 5 is a top plan view thereof;

FIG. 6 is a bottom plan view thereof;

FIG. 7 is a front elevational view thereof;

FIG. 8 is a cross-sectional view, enlarged, taken along the line 8—8 of FIG. 5;

FIG. 9 is a top plan view of a first one-third portion thereof;

FIG. 10 is a top plan view of a middle one-third portion thereof; and,

FIG. 11 is a top plan view of a last one-third portion thereof.

FIG. 2

FIG. 1

FIG. 3

FIG. 9

FIG. 10

FIG. 11
